UNITED STATES PATENT OFFICE.

WILLIAM P. CURRY, OF SYRACUSE, NEW YORK.

MACHINE FOR CUTTING BEVELS.

1,336,731.

Specification of Letters Patent. Patented Apr. 13, 1920.

Application filed July 5, 1919. Serial No. 308,700.

To all whom it may concern:

Be it known that I, WILLIAM P. CURRY, a citizen of the United States, residing at Syracuse, in the county of Onondaga and 5 State of New York, have invented certain new and useful Improvements in Machines for Cutting Bevels, of which the following is a specification.

This invention relates to improvements in 10 machines for cutting bevels, and has for its object to provide novel and simple mechanism for cutting circular bevels on electro-types and like articles, for facilitating locking the types in place during the printing 15 operations. A further object is to provide a plurality of beveling and profiling knives for cutting circular bevels and for turning electroplates and other articles to uniform diameters simultaneously, the said knives 20 being mounted in a novel power-driven holder which is rotated at high speed, the beveling and profiling knives being mounted in alternate order. A further object is to provide a novel manually operated mechanism 25 for supporting and rotating the electro-plates in the opposite direction to that of the knives. A further object is to provide novel means for frictionally clamping and holding the electro-plates during the 30 beveling and profiling operations. And a further object is to provide means for adjusting different parts of the device.

I attain these objects by the means set forth in the detailed description which follows, and as illustrated by the accompanying drawings, in which—

Figure 1 is a front side elevation of the complete machine; showing the device in the act of completing the beveling and profiling of a piece of work. Fig. 2 is an end elevation of the device; showing a rough piece of work ready to be operated upon by the beveling and profiling knives, the said knives being shown in released position. Fig. 3 is a horizontal section, taken on line 3—3 of Fig. 1. Fig. 4 is a vertical cross-section, taken on line 4—4 of Fig. 2; showing the mechanism for frictionally gripping the work; also showing the mechanism 40 for rotating the work during the cutting operation. Fig. 5 is an enlarged top-plan view of the knife holder. Fig. 6 is an edge view of the same. Fig. 7 is a top-face view of one of the electro-plates before 45 being operated upon by the knives. Fig. 8 is respectively a top-face and an edge view

of the electro-plate after the same has been operated upon.

Electro-plates used for printing the cardboard stoppers for milk bottles, are usually 60 cast in large numbers in a single plate or part. These plates are afterward sawed for separating the individual electro-plates. The saw leaves the plates with ragged and irregular margins, each of which must be 65 trimmed and then finished with a circular bevel flange, and the diameters of all of the plates must be uniform, so as to facilitate securing the plates to the beds of the printing presses in close formation for making 70 multiple impressions of the types. Heretofore the rough plates have been turned and beveled in lathes, and the work has been slow and tedious. The object of the present invention is to provide novel means for 75 rapidly and accurately performing the work and for greatly reducing the cost of such work. A detailed description of my improvement follows:

In the drawings, 2 represents the base of 80 the machine, upon the top of which is mounted the usual stationary bed 3. 4 is an upright standard which rises from and is made rigid on the base 2, and has a forwardly projecting arm 4' which supports 85 the power-driven cutting mechanism. 5 is a vertical spindle, the upper end of which is fitted with a pulley 5', and 6 is a belt which drives the pulley and spindle. Below the arm 4' is a bracket 8, supported at one 90 end by the standard 4, the opposite end comprising a bearing 8' for the spindle 5. Below the bearing 8' the spindle is fitted with a chuck 9, which detachably receives the tapering shank 10' of a knife-holder 10. 95 The holder 10 is substantially square and is provided with similar grooves 10^a in its four edges, in which two beveling and two profiling knives, 11 and 11', are adjustably disposed in alternate order, as shown in 100 Figs. 1, 2, 3, 5 and 6. The knives are held in place by washers 10^b and bolts 10^c. The cutting edges of the beveling knives 11 incline downwardly and inwardly, while the cutting edges of the profiling knives 11' are 105 arranged vertically. The chuck 9 and the tool-holder 10 are raised and lowered by means of a lever 13, which is pivoted to the bracket 8, at 8^a, said lever having a pawl 13' which engages a ratchet gear 14, for 110 locking the spindle and tool-holder in the various positions, in the usual manner. The

moving of the lever 13 in the direction indicated by the arrow in Fig. 2 lowers the knives 11 and 11' into the cutting position, shown in Fig. 1.

5 The mechanism which supports and operates the electro-types or plates 12, will now be described: 3' represents a movable bed which is supported by the bed 3 and is adjustable by means of a crank 3^a for positioning the electro-plates relatively to the path of the knives 11—11'. 15 is a hollow substantially cylindrical body, having a radial arm 15'. The body 15 is rigidly mounted on the bed 3' by bolts 15^a which 10 pierce a flange 15^b. The electro-plates 12 or like articles are supported horizontally by a rotatable disk or part 16, which is mounted centrally on the body 15. The disk 16 is rotated by a shaft 17, whose lower 15 end is fitted with a relatively large bevel-gear 18, which is driven by a pinion 19, the latter being mounted on a shaft 20 which is journaled in the arm 15', the outer end of said shaft being fitted with a crank 20', 20 by which all of said parts are rotated during the beveling and profiling operations. The shaft 17 operates on ball bearings 21, comprising a collar-like member 21' which is rigid on said shaft by a pin 21^a, and a 25 stationary member 21^a, which is made rigid to the interior of the body 15 by bolts 21^b. The shaft 17 has a flange 17' disposed between the gear 18 and the member 21^a, the said gear being held against the flange by 30 a washer 22 and a nut 22'. 23 is a bracket, whose vertical arm is anchored in the arm 15', the horizontal arm of said bracket extending forwardly, and its free end being perforated in line axially with the disk 16. 35 24 represents a bushing which reciprocates vertically in the perforated end of the bracket 23, to the lower end of which is fitted rigidly a collar 25, while to the upper end of said bushing is fitted a thrust-collar 26, which is slotted at its opposite sides to receive the arms 27' of a yoked lever 27, by means of which the bushing 24 is reciprocated vertically. The collars 25 and 26 are spaced apart sufficiently to allow the 40 said vertical movements. The lever 27 is loosely pivoted between parallel plates 28, which are secured to the opposite sides of the bracket 23 by bolts 28'. 29 represents a spindle which passes through and is rotatable in the bushing 24, the said spindle being held in place by a collar 30 which is made rigid to its upper end by a screw 30', and also by a disk 31 which is rigidly secured to the lower end of the spindle. In 45 order to eliminate friction between the collar 25 and the disk 31, the meeting faces of said parts comprise the opposing members of a ball-bearing 32. The disk 31 is positioned directly above and in line axially with the disk 16 from which it is spaced

sufficiently to permit of the free insertion and removal of the electro-plates 12. The plates 12 are held in the proper position during the beveling and profiling operations by the frictional engagement of the disk 31, 70 when the latter is held against the top-face of the plates 12 under sufficient pressure to prevent accidental release of the plates, and at the same time allowing the plates to be rotated during the cutting operations, as 75 described. The lever 27 is rocked for moving the friction disk 31 into and out of engagement with the electro-plates 12 by a link 33, which in turn is operated by a hand-lever 34, the latter being pivoted between 80 the plates 28. The full lines in Fig. 1 show the operated position of the lever 34, while the dotted lines in Fig. 1 and the full lines in Fig. 4 show the released position of said lever, which breaks the frictional engagement of the disk 31 with the electro-plates 12. 85

The operation of my improved beveling device is as follows: At the start of the operation, the lever 13 should be in the position shown in Fig. 2, and the hand lever 34 90 should be in the dotted position shown in Fig. 1. The operator first takes one of the untrimmed plates 12, having the irregular margins 12' (see Fig. 7), and places it upon the disk 16 with its impression face upwardly. The handle 34 is then pulled downwardly (see full lines in Fig. 1), which rocks the lever 27 in the direction for bringing the swiveled disk 31 down upon the top face of the plate 12 and exerting sufficient 100 pressure thereon to frictionally hold the plate 12 from displacement, but still allowing said plate to be rotated by the manual operation of the crank 20', as described. The operator then pulls the lever 13 forwardly for lowering the knives 11—11' from the released position shown in Fig. 2 to the cutting position shown in Fig. 1. The knives being constantly rotated by the belt 6 immediately begin cutting the portions 110 of the edges 12' of the plates 12 which project into the path of the knives. The operator next starts turning the crank 20', which rotates the disk 16, the electro-plate 12 and the disk 31 until the beveling and 115 profiling work is done. The profiling knives 11', whose edges are vertical, are employed for turning the plates 12 to the true diameter, and at the start of the cutting operations, the knives 11' trim or cut the irregular 120 edges 12' of the plates, and by the time the said knives have finished their work, the beveling knives 11 are engaged in cutting the bevel flanges 12^a. The arrows in Figs. 3 and 5 show the direction of rotation of the 125 knives 11—11' relatively to that of the plate 12. The knives preferably rotate at a high speed. The rotation of the plates 12 being effected manually, naturally varies in speed, but should be as rapid as possible, so as to 130

insure rapid and accurate work. The work of beveling each plate 12 consumes but a few seconds time. The means herein shown and described for frictionally gripping and holding the plates 12 also serves to position said plates so that the bevel flanges 12^a are truly concentric to the impression faces of the plates.

Having thus described my invention, what I claim as new and desire to secure by Letters Patent, is—

1. A machine for cutting circular bevels, including a plurality of knives, a power-driven holder for said knives, a work support, a train of gears for rotating said support for bringing the work into the path of said knives, a swivel member for frictionally clamping the work to said support, and a vertically reciprocatable part for operating said swivel member.

2. In a machine for cutting circular bevels, a power-driven tool-holder adapted to be moved into and out of cutting position, beveling and profiling knives carried by said holder, a rotary work support adapted for positioning the margins of the work in the path of said knives, means for manually rotating said support, and a swivel device for frictionally holding the work while the latter is being rotated.

3. In a machine for cutting circular bevels, a plurality of beveling and profiling knives, a power driven holder for said knives adapted to be reciprocated vertically for moving said knives into and out of cutting position, a manually operable work support adapted to position the work in the path of said knives, and a swivel device adapted to frictionally hold the work against accidental release while said knives are performing the cutting operations.

4. In a circular beveling machine, a plurality of beveling and profiling knives arranged in alternate order, a power-driven holder for said knives, a work support, a train of gears for rotating said support for

bringing the margins of the work into the path of said knives, a swivel clamping device for centering and frictionally holding the work on said support, and means for exerting sufficient pressure upon said clamping device to prevent the accidental release of the work during the beveling operations.

5. A beveling and profiling machine, including a power-driven spindle, a tool-holder supported and rotated by said spindle, a plurality of beveling and profiling knives carried by said holder and adjustable therein, said knives arranged in alternate order, a rotatable work support, the axis of said support being parallel to the axis of said tool holder, means for rotating said support in a direction opposite to the direction of rotation of said tool holder, and means for frictionally clamping the work to the said support.

6. A beveling and profiling machine, including a spindle, a tool-holder supported and rotated by said spindle, a plurality of beveling and profiling knives carried by said holder, a rotatable work support, the axis of said support being parallel to the axis of said spindle, means for rotating said support, means for frictionally clamping the work to said support, a rocking lever for reciprocating said clamping means, and means for rocking said lever.

7. A beveling and profiling machine, including a power-driven spindle, a tool holder supported and rotated by said spindle, a plurality of knives carried by said holder, a work support rotatable on an axis parallel to the axis of said spindle, a train of gears for operating said support, a thrust-bushing, means for reciprocating said bushing, and a clamping disk disposed in line axially with said support and journaled in said bushing adapted to frictionally hold the work during the rotation of said support.

In testimony whereof I affix my signature.

WILLIAM P. CURRY.
